US00D950768S

(12) **United States Design Patent** (10) **Patent No.:** **US D950,768 S**
Conway et al. (45) **Date of Patent:** **** May 3, 2022**

(54) **COLLECTION AND TRANSPORT DEVICE**

(71) Applicant: **Bioplast Manufacturing, LLC**, Bristol, PA (US)

(72) Inventors: **Christopher Conway**, Moorestown, NJ (US); **Brian Conway**, Stratford, NJ (US)

(73) Assignee: **Bioplast Manufacturing, LLC**, Bristol, PA (US)

(**) Term: **15 Years**

(21) Appl. No.: **29/681,084**

(22) Filed: **Feb. 22, 2019**

(51) LOC (13) Cl. **24-02**

(52) U.S. Cl.

USPC **D24/224**

(57) **CLAIM**

The ornamental design of a collection and transport device, substantially as shown and described.

DESCRIPTION

FIG. 1 is a side elevation view of a collection and transport device with the screw cap removed in accordance with the present invention shown separately for ease of illustration; FIG. 2 is a cross sectional view thereof;

FIG. 3 is a side elevation view of the screwcap used in accordance with the collection and transport device of the present invention shown separately for ease of illustration;

FIG. 4 is a cross sectional view thereof;

FIG. 5 is a top plan view thereof;

FIG. 6 is a top exploded perspective view of a collection and transport device of the present invention;

FIG. 7 is a bottom exploded perspective view of thereof;

FIG. 8 is a cross sectional side view of a collection and transport device in accordance with the present invention.

FIG. 9 is a top perspective view of a collection and transport device with the screw cap removed of the present invention shown separately for ease of illustration; and,

FIG. 10 is side elevation view of a collection and transport device of the present invention.

1 Claim, 7 Drawing Sheets
